UNITED STATES PATENT OFFICE.

IVEY O. HUCKS, OF ROSEMARY, NORTH CAROLINA, ASSIGNOR TO DRAPER CORPORATION, OF HOPEDALE, MASSACHUSETTS, A CORPORATION OF MAINE.

LET-OFF MECHANISM FOR LOOMS.

Application filed October 14, 1927. Serial No. 226,105

This invention relates to let-off mechanism for looms and has for its main object to provide a simple and efficient means by which the warp beam may be freed from its actuating mechanism for hand rotation whenever necessary.

It is the further object of the invention to provide such a means which will leave both hands of the operator free to manipulate the warp beam.

The nature and objects of the invention will appear more fully from the accompanying description and drawings and will be pointed out in the claims.

This invention has to do with a type of positively driven let-off mechanism wherein the warp beam is geared to a transmitting shaft, which shaft carries a pinion driven from suitable mechanism connected with the loom, which pinion, when connected to the transmitting shaft, acts thereby to transmit the required rotary movement to the warp beam.

In this invention the gear connection between the warp beam and transmitting shaft is not affected, but a suitable means is provided for connecting and disconnecting the pinion to the transmitting shaft and for locking this connecting and disconnecting means in its disconnecting position when required. Thus the operator, after locking the mechanism in disconnecting position, has both hands free to manipulate the warp beam, as in the case of a pick-out or otherwise, and the pinion also remains connected to the mechanism by which it is driven.

As the invention thus has to do with only one feature of the loom mechanism and as the general type of let-off mechanism with which the invention is concerned is well known and familiar to those skilled in the art, it is only necessary here to illustrate and describe those parts of a loom particularly concerned with the invention, together with a preferred form of the invention.

In the drawings:

Fig. 1 is a side elevation of a portion of a loom and let-off mechanism.

Fig. 2 is a front elevation of the construction shown in Fig. 1 taken partially in vertical cross section on the line 2—2 of Fig. 1.

Fig. 3 is an enlarged detail in front elevation and partially in cross section showing the transmitting shaft and connected parts.

Fig. 4 is a view in cross section taken on the line 4—4 of Fig. 3.

In the construction illustrated, the let-off mechanism comprises a transmitting shaft 1, preferably extending across the loom and journalled in suitable bearings, such as 2, in the loom sides 3. This shaft is provided with a small gear 4 secured thereto as by the set screw 5 and this gear meshes with the usual gear 6 fast on the warp beam 7. A similar gear may be employed, if desired, at the opposite side of the loom.

The operating mechanism is shown as comprising a vertical shaft 8 journalled in suitable bearing brackets 9, extending from the loom side. This shaft 8 carries a ratchet wheel 10 driven by a pawl 11 operated from a link 12 extending to a suitable moving part of the loom. The shaft 8 also carries a worm 13 meshing with a worm wheel pinion 14 loose on the shaft 1.

Consequently it will be seen, when the pinion 14 is fast to the shaft 1 and the shaft 8 is rotated under the operation of the link 12, that rotary motion will be transmitted to the warp beam, thus securing the let-off action, all in a well known and familiar manner.

In the preferred form of construction embodying this invention, the shaft 1 at the left of the bearing 2 has secured thereto by means of the set screw 15 a collar 16 and a similar collar 17 is secured by a set screw 18 spaced from the collar 16 to the end of the shaft 1. The pinion 14 is provided with a hub 19 projecting therefrom toward the collar 17 and is also provided with a recess fitting over the collar 16. A helical spring 20 abutting the collar 17 and the hub 19 of the pinion 14 serves normally to force the pinion against the collar 16.

The pinion 14 has secured to its face a U-shaped bridge member 21. A hook-shaped clutch pin thus presenting a straight body 22 and a laterally extending arm 23 is mounted to slide longitudinally and parallel with the shaft 1 in the bridge 21 and pinion 14. This clutch pin is spring-impelled toward the collar 16 by a helical spring 24 surrounding the pin and abutting the bridge 21 and a projection 25 on the clutch pin body 22.

The collar 16 is provided with a hole, and preferably with a plurality of holes, 26 spaced at the same distance from the axis of the shaft 1 as the hole in the pinion through which the clutch pin 22 slides. Thus it will

be seen that the clutch pin is normally spring-
impelled so as to pass into a hole 26 and thus
connect the pinion 14 to the collar 16 and
thus to the shaft 1. This is the normal con-
dition of the mechanism and in this condition
the driven pinion 14 imparts its movement
to the warp beam.

When it is desired to have the warp beam
10 free for rotation, this clutch pin 22 is slid
longitudinally until it is withdrawn from the
hole 26 in the collar 16 and then it is turned
until its arm 23 extends over and locks against
the bridge 21. Thus the pin is locked in its
15 retracted position. While the pinion 14 thus
remains in connection with the worm 13, it is
freed from the shaft 1 and thus the warp
beam is free to rotate.

It will also be seen that the operator hav-
ing once disconnected the pinion 14 from the
20 shaft 1 and locked the clutch pin 22 in re-
tracted position, has both hands free to
manipulate the warp beam.

When it is desired to restore the operation
of the let-off mechanism, the operator simply
25 turns the clutch pin 22 until the arm 23 is
out of line with the bridge 21, when the clutch
pin, impelled by the spring 24, slides into en-
gagement with the hole 26 and the operation
of the let-off mechanism is resumed.

30 Having thus described the invention, what

is claimed as new, and desired to be secured
by Letters Patent, is:

1. A let-off mechanism for looms comprising
a transmitting shaft, a warp beam geared
to said shaft, a pair of spaced collars fast on
35 said shaft, a driven pinion loose on the shaft
and abutting one collar, a spring on the shaft
between the pinion and the other collar acting
to force the pinion against the first collar, the
pinion having a clutch pin mounted to slide
40 therein parallel with the shaft and the first
collar having a hole to receive the pin, and a
spring engaging the pin and acting normally
to force it into, and maintain it seated in,
45 said hole.

2. A let-off mechanism for looms comprising
the construction defined in claim 1, to-
gether with means for locking the clutch pin
in retracted position.

3. A let-off mechanism for looms comprising
the construction defined in claim 1, in
which the first collar is provided with a plu-
rality of holes arranged equidistant from the
50 shaft axis and each adapted to receive the
clutch pin whereby the pinion and collar may
be clutched together in various relative ro-
tary positions.

In testimony whereof, I have signed my
name to this specification.

IVEY O. HUCKS.
